UNITED STATES PATENT OFFICE.

JOHN E. BURKHARDT, OF QUINCY, MASSACHUSETTS, ASSIGNOR TO BETHLEHEM SHIP-BUILDING CORPORATION.

FLUID-CIRCULATING MEANS.

Application filed March 17, 1927. Serial No. 175,972.

My invention relates to a mechanism for circulating fluid through a system, wherein a main, fluid impelling means is supplemented by an auxiliary means, whenever the rate of flow due to the main means is insufficient. More specifically, it relates to an arrangement of means whereby the movement of a vessel over a body of water forces water through a circulation system, there being an auxiliary, power driven impeller to supplement the impulsion due to the movement of the vessel, when for any reason, the latter is insufficient.

My invention consists of a system for circulating fluid having means for impelling fluid through a conduit, an auxiliary, power driven impeller, reacting with the stream flow, when idle, so as to be moved into a non-obstructing position, but when positively driven, so reacting with the fluid as to be returned into an operative position.

While, in the description which follows, the specific embodiments used for illustrating my invention are directed to condenser cooling systems, wherein a vessel by its movement scoops up water and forces it through the condensers, it is to be clearly understood that my invention in its broader aspects is not limited to such applications of the inventive thought, but is applicable to any fluid circulating system.

Referring to the drawings which, diagrammatically present two embodiments of my invention:

Fig. 1 is a longitudinal elevation of a portion of a ship showing a steam condenser in combination with a scoop and conduits for carrying the water to and from the condenser together with an auxiliary impeller;

Fig. 2 is a sectional elevation of the ship, on the line 2—2 of Fig. 1, showing this equipment in duplicate;

Fig. 3 is a longitudinal section on a larger scale, showing a portion of the conduit from the scoop to the condenser, together with the auxiliary impeller;

Fig. 4 is an enlarged transverse view, partly in section, of the mechanism for driving the auxiliary impeller;

Fig. 5 is a transverse view of the auxiliary impeller;

Fig. 6 is a longitudinal section of the end of the pump shaft extending outside of the conduit; and

Fig. 7 is a longitudinal section of a portion

of the conduit and the auxiliary impeller in a modification.

An ordinary condenser 1 receives water from the body over which the vessel is passing by means of scoop 2 which projects from the skin of the ship 3, the movement of the vessel forcing the water up through the conduit 4 which comprises the more or less restricted duct 5 and the enlarged portion 7, where it joins the condenser. From the condenser the water passes overboard through ducts 8 and 6. The inlet and outlet connections are provided respectively with shut-off valves 9 and 10.

To supplement the propulsion of water through the condenser, when for any reason the flow of water due to the movement of the vessel becomes insufficient, or to take the place thereof when, for example, the vessel is driven astern, there is provided a power driven impeller 11. This impeller is fixed at the end of shaft 12, being secured on the tapered end 13 thereof by means of key 14 and nut 15.

Shaft 12 is journaled in bearings 16 and 17 located within duct 5, these bearings being rubber lined or of any construction suitable for running in water. A gland 18 and packing 19 are provided to prevent leakage at the point where the shaft passes through the wall of duct 5.

Shaft 12 passes through the hub of worn wheel 20 with which it is constrained to rotate, the structure for this purpose consisting of a squared portion 21 of shaft 12 which fits into a correspondingly shaped hole 22 in the worm wheel hub, the squared portion 21 of the shaft being of smaller diameter than the body of the shaft so that a shoulder 23 is provided. While constrained to rotate with the worm wheel the shaft is free to slide axially with respect thereto between certain limits. The projecting portion 24 of the shaft is of smaller diameter than portion 21. Hand wheel 25 is journaled on portion 24 and is secured thereto by means of washer 26 and nut 27. Shoulder 23 and hand wheel 25 in conjunction with facings on the hub of wheel 20 serve to limit the axial movement of shaft 12 relative to worm wheel 20.

This worm wheel is journaled in bearings 28 with thrust facings 29 formed in the two halves 30 and 31 of the gear housing, of which the lower half 30 may be integral with duct 5 as shown. Wheel 20 meshes with worm 32 which is integral with worm shaft

33. This latter shaft is journaled in bearings 34 and 35 secured in housing 31, and is provided with suitable thrust collars 36 and 37.

5. Worm shaft 33 extends through the wall of the gear housing and is driven by a steam turbine 38 connected to shaft 33 through a flexible coupling 39. The interior parts of the turbine are so arranged that when steam is admitted worm shaft 33, worm wheel 20, shaft 12 and impeller 11 rotate in the directions shown by the curved arrows in Figs. 3 and 4.

The manner of operation of my invention 15 is as follows:

Valves 9 and 10 are normally open, being closed only when the vessel is not in operation. Let it be assumed that the vessel is moving ahead in the direction shown by 20 arrow 40 in Figs. 1 and 3 and that scoop 2 is forcing a sufficient stream of water into condenser 1 through the conduit 4, and thence overboard through ducts 8 and 6. Under these circumstances the steam connection to 25 turbine 38 will be closed, and the shaft 12 will not be positively driven. The flow of water past impeller 11 will cause rotation thereof and produce a thrust on face 41, causing the impeller and shaft to slide axially in the direction of arrow 42, as indicated in Fig. 3, until hand wheel 25 comes into contact with the hub of worm wheel 20, as shown in dotted lines. The impeller is then in the enlarged portion 7 of the conduit, 30 as shown by dotted lines, and offers much less resistance to the flow of water from the scoop to the condenser, the quantity thereby supplied to the condenser being materially greater than if the impeller were to remain 35 in its original position within duct 5.

Since the velocity of the water in portion 7 is much less than in duct 5, the tendency of the water to turn the impeller is greatly reduced.

45. If now the engines of the vessel are reversed and the vessel is driven astern, in the direction of arrow 42 as shown in Fig. 1, the movement will no longer cause water to be forced through the condenser. Steam is now 50 admitted to turbine 38, causing rotation of the impeller in the direction shown by the curved arrow, or increasing the speed of rotation, if the impeller is already rotating. When the speed of rotation is sufficiently 55 great there is developed, on the after face 43 of the impeller, a thrust which causes it, together with the shaft 12, to slide axially forward into position shown in full lines, in 60 which position shoulder 23 on shaft 12 is in contact with the facing within the hub of worm wheel 20. The continued rotation of the impeller will now pump water from the sea through the conduit into the condenser and thence overboard through ducts 8 and 6.

65. Obviously the auxiliary impeller may be

used at other times; it being clear that it may be employed at any time when the propulsion of water due to the movement of the vessel is insufficient. Obviously it may be used even when the vessel is going ahead to assist the 70 action of the scoop. Assuming, as before, that the vessel is moving in the direction of arrow 40 and steam is shut off from turbine 38, water being impelled through the conduit into the condenser by the action of scoop 2, 75 impeller 11 being in the position shown by dotted lines and not rotating, or rotating slowly in the direction shown by the curved arrow. If steam is now admitted to the turbine 80 38 it would cause the impeller to rotate in the direction of the curved arrow or would increase its speed if it is already rotating. The thrust developed on the after face of 43 of the impeller would cause it and the shaft 12 to slide into the position of full lines as 85 previously set forth. The impeller now imparts to the water on which it acts an additional momentum in the direction of the condenser and will thereby increase the flow of water from the sea. 90

It is clear from the foregoing that when the impeller is not being driven the flow of the water past it will bring about a reaction between it and the water so as to cause it to assume the inoperative and non-obstructing 95 position shown by dotted lines, while the positive driving of the impeller will cause it to react with the fluid to cause it to return to the operative position shown by full lines.

The position of the impeller within the conduit is always apparent from the position of hand wheel 25. If because of excessive friction in the mechanism, the impeller does not promptly assume the desired position it may be assisted manually by taking hold of the hand wheel 25 and pushing or pulling axially as required. To this end the hand wheel is journaled on shaft 12 as above indicated so that when it is handled it does not rotate with the shaft. Obviously, where friction conditions are such that manual assistance is not necessary the hand wheel may be replaced by a suitable collar or any other means for limiting the axial motion of the shaft. 100

In the modification shown in Fig. 7 structure is indicated whereby the axial movement of the impeller is effected without its supporting shaft partaking of the movement. Impeller 11' instead of being fixed to shaft 12' is slidably splined thereto and therefore may move along such shaft between bearings 16 and 16', these being the limits of the axial movement. The connection between shaft 12' and the turbine is similar to that in the form already described, except that the shaft is so keyed to worm wheel 20' that it is prevented from axial movement relative to the wheel. In this embodiment of the invention, when the impeller is idle 115 the flow of the water reacts therewith to cause 120

125

130

it to move along the shaft into its inoperative, non-obstructing position, shown in the dotted lines. When the turbine is put in operation and the shaft 12' positively driven the 5 rotation of the impeller so reacts with the water as to cause the impeller to slide into the operative position.

In thus describing these specific embodiments of the invention, it is not intended to 10 limit the protection sought for, especially in its broader aspects, to condenser cooling systems. Moreover, it is not intended that the broader claims should be limited to devices in which one of the flow impelling means is 15 due to the movement of a vessel or other body. Obviously, the invention in its broader aspects is applicable to circulation systems in which various types of pumps are employed to force liquid through a conduit or other 20 body. As above pointed out, it is considered that the invention broadly is in the idea of a combination of fluid impelling means, one supplementing the other, and being automatically movable into and out of operative position 25 depending upon whether or not it is positively driven.

Certain expressions used in the description and claims are not to be given too restrictive a construction. For example, when referring 30 to the auxiliary impeller as being "idle" it is not intended necessarily to mean that this impeller has no movement whatever, but that it is not being positively driven. When one of the fluid impelling means is referred to 35 as "supplemental" it is not to be taken necessarily to mean that it acts in a subordinate or to a lesser extent than the other, but merely that to a certain extent each aids or supplements the other.

40 While I have shown my invention in a plurality of forms, it will be obvious to those skilled in the art that it is not so limited, but is susceptible of various other changes and modifications without departing from the 45 spirit thereof, and I desire, therefore, that only such limitations shall be placed thereupon as are imposed by the prior art or as are specifically set forth in the appended claims.

Having described my invention, what I 50 desire to claim is as follows:

1. In a fluid circulation system, a conduit having a greater cross-sectional area following a lesser along the line of flow, power driven means for positively impelling fluid 55 through the conduit, a supplemental flow impeller mounted to be movable from a place of one cross-sectional area to a place of a different cross-sectional area, means for driving the supplemental impeller, said impeller when 60 idle being moved by the action of the stream

flow into a place of greater cross-sectional area and when positively driven reacting with the fluid to move into a place of lesser cross-sectional area.

2. In a fluid circulation system, a conduit 65 having a greater cross-sectional area following a lesser along the line of flow, power driven means for positively impelling fluid through the conduit, a supplemental flow impeller mounted to be movable from a place of one cross-sectional area to a place of a 70 different cross-sectional area, means for driving the supplemental impeller, means whereby the supplemental impeller when idle reacts with the stream flow to be moved to a place of greater cross-sectional area and when positively driven be moved to a place of lesser cross-sectional area.

3. In a circulation system, primary power 75 driven means for positively forcing liquid 80 through a conduit, supplemental means comprising a rotary impeller within the conduit, longitudinally movable between limits, means for driving the rotary impeller independent of the said primary means, and means whereby the stream flow due to the primary means reacts with the rotary impeller when idle to move it to a place of greater cross-sectional area of the conduit, and means whereby the 90 rotary impeller reacts with the fluid upon being positively driven to be returned to a place of lesser cross-sectional area.

4. In a marine engine installation, a cooling 95 system having inlet and outlet conduits, a scoop at the entrance of the inlet conduit, a shaft extending through the wall of the inlet conduit, an impeller within said conduit, 100 said impeller being constrained to rotate with said shaft, but free to slide axially between parts of the conduit having different cross-sectional areas, and means whereby said impeller reacts with the fluid to be moved into the greater cross-sectional area when idle and to be moved into the lesser cross-sectional area when positively driven.

105 5. In a marine engine installation, a cooling system having inlet and outlet conduits, a scoop at the entrance of the inlet conduit, for effecting a flow of liquid therethrough upon movement through a body of liquid, a 110 flow impeller in the inlet conduit, means for driving the impeller, means for rendering the impeller relatively non-obstructive to flow when idle, and means for restoring the impeller to operative condition when positively 115 driven.

In testimony whereof I hereunto affix my signature.

JOHN E. BURKHARDT.
